UNITED STATES PATENT OFFICE

173,247

JEWEL CASE

Eileen Budd White, Tampa, Fla.

Application December 8, 1952, Serial No. 22,592

Term of patent 14 years

(Cl. D80—11)

To all whom it may concern:

Be it known that I, Eileen Budd White, a citizen of the United States, residing at Tampa, in the State of Florida, have invented a new, original, and ornamental Design for a Jewel Case, of which the following is a specification, reference being had to the accompanying drawing, forming a part thereof.

I claim:

The ornamental design for a jewel case, as shown.
